of the City of Troy in the County of Rensselaer and State of New York, have invented a new and improved design in the finish of a stone which to distinguish from other stones I call the Trojan Parlor, and I do hereby declare that the following is an exact description. - The nature of my invention consists in the design and outer finish upon the feet bottom, ends, front, back, top, and perpendicular flues, connected with the base horizontal flues, all of which may be seen in figures 1 and 2, 5 and 6, on the within drawings.

To enable others skilled in the art to make and use my invention, I will proceed to describe its design and configuration. - I construct my stone with a bottom base in a horizontal Ogee form which I ornament with carved moulding and vines, as may be seen in figures 1 and 2, letters A, and B. Upon this base lies the bottom plate to the fire box made in the form to fit the base, ornamented with leaves and vines as seen in Fig. 1 and 2, letter C; the fire box or body at top and bottom has a large Ogee moulding carved with leaves as seen in Figs 1 and 2, letter D; at each corner is an upright Ogee, with leaves, inside of which is a turned head, the panel on front, back and ends is finished with leaves, checks and vines all as seen in Figs 1 and 2 letter E; the top plate is carved in a form as seen in Figs 1 and 2 letter F; the back upright flues are finished with vines, checks and leaves as seen in Figs 1 and 2 letter G.

What I claim as my invention and desire to secure by letters patent, is the design and of the above described stone plates, as herein described.
